UNITED STATES PATENT OFFICE.

WILLIAM P. DRUMHELLER, OF SPRINGFIELD, MASSACHUSETTS, ASSIGNOR TO WILLIAM CARTER COMPANY, OF NEEDHAM HEIGHTS, MASSACHUSETTS, A CORPORATION OF MASSACHUSETTS.

YARN CONTROL FOR KNITTING MACHINES.

Application filed April 19, 1923. Serial No. 633,140.

To all whom it may concern:

Be it known that I, WILLIAM P. DRUMHELLER, a citizen of the United States, and a resident of Springfield, in the county of 5 Hampden and State of Massachusetts, have invented an Improvement in Yarn Controls for Knitting Machines, of which the following description, in connection with the accompanying drawings, is a specification, 10 like characters on the drawings representing like parts.

This invention relates to yarn control for knitting machines, and more particularly to combinations including improved means 15 for effecting a positive, controlled feed of the yarn or yarns to the needles of the machine, or to the needles and the immediately cooperating instrumentalities thereof and including fluttering-absorption vibratory members, and in such a manner as to prevent 20 press-offs in the event of yarn breakage, but I do not herein claim positive feeding devices per se with the immediately associated guides, as such matter is claimed in 25 my application Serial No. 684,330, which is a continuation as to the common subject matter hereof.

In order that the principle of the invention may be readily understood, I have 30 disclosed in the accompanying drawings a single embodiment of my invention.

In said drawings,—

Fig. 1 is a front elevation of a circular knitting machine of the dial type having my 35 invention applied thereto;

Fig. 2 is a front elevation on an enlarged scale of the upper part of the mechanism shown in Fig. 1 and representing two only of the yarn packages and the means for 40 effecting the positive feed of yarn therefrom;

Fig. 3 is a plan view, but taken upon the line 3—3 of Fig. 1 and showing a series 45 of yarn packages;

Fig. 4 is a plan view taken from above the entire mechanism but showing parts in dotted lines and parts as broken away;

Fig. 5 is a transverse vertical central section taken through the upper part of the machine and showing two pairs of feed rolls;

Fig. 6 is a side elevation of a pair of said feed rolls;

Fig. 7 is an end view of the feed rolls shown in Fig. 6, looking from the left in Fig. 6;

55

Fig. 8 is an end view of said feed rolls looking from the right in Fig. 6;

Figs. 9 and 10 are diagrams indicating the operation of the mechanism and the relation of the positive feed to the stop mechanism 60 in preventing press-offs in the event of yarn breakage;

Fig. 11 is a side elevation of a part of the mechanism and showing different positions of one of the members thereof;

65

Fig. 12 is a plan view of a somewhat modified form of a part of my invention;

Fig. 13 is an end elevation of the construction shown in Fig. 12; and

Figs. 14 and 15 are side elevations of said 70 modification viewed from the left and right in Fig. 13.

My invention may be applied to any desired type of knitting machine, as, for example, either straight or rotary, and with 75 the latter type it may be employed with a rotated needle cylinder or rotated cam cylinder. I have chosen to represent the invention as applied to a circular type of knitting machine having a rotated needle cylinder and a flat dial. I desire it to be understood that my invention is not limited to the disclosed or any other particular type of machine, although peculiarly cooperating with the circular type having a plurality of yarn 85 feeds, and especially cooperating with the rib type of circular knitting machine.

Referring more particularly to the drawings, the bed plate of the machine is indicated at 1 in Fig. 1 as supported upon suitable 90 uprights 2 extending from a base 3. The cam cylinder is indicated generally at 4, and the dial plate at 5. Upstanding from the dial plate is a central stationary support 6 extending through a cross head 7 itself 95 supported upon suitable posts 8, 9 from the bed plate. Extending upward from the bed plate 1 is a bracket 10 having an inwardly curved upper portion 11 having at its extreme end a cylindrical opening 12 in which is 100 received and secured a central stationary upright 13, which at its lower end supports a portion of the stop mechanism indicated generally at 14. Said stop motion in-

cludes an upper ring or disk like member 15, an intermediate ring 16 therebelow having pivoted therein a number of vibratory members 17 counterweighted as indicated at 18, the number of said members corresponding to the number of yarns or threads supplied to the needles. Below the ring 16 is a ring 19, over which the various yarns pass, being guided through the eyes 20, 21 of the pivoted members 17.

The central upright 13 carries near its upper end a disk like member 22 from which extend supports for the yarn packages. Said supports may be of any suitable form, but they are here shown as rods 23 extending outward and downward and terminating suitably to support the yarn packages 24 equalling in number the yarns or threads supplied to the knitting mechanism.

Fast upon the upper end of the central upright 13 is a head or box-like frame 25 shown in vertical section in Fig. 5 as somewhat conical in form and having a lateral opening 26 constituting a bearing for a horizontal shaft 27. Said shaft 27 is supported at its outer end in a bearing 28 provided in a bracket 29 itself carried by the upper end of a vertical rod or upright 30 supported by a bracket 31, which in turn is suitably supported upon the framing. The main drive shaft of the machine is indicated at 32 as having thereon fast and loose pulleys 33, 34 and a beveled pinion 35 by means of which the needle cylinder is rotated. From said main drive shaft 32 extend suitable connections not herein necessary to indicate for imparting rotary movement to a vertical shaft 36 which at its upper end has a beveled pinion 37 meshing with and driving a similar pinion 38 fast upon the said shaft 27, thereby rotating the latter at suitable speed.

Upon the inner end of the shaft 27 is fast a beveled pinion 39 meshing with an annular series of teeth 40 upon the upper face of a plate gear 41, the hub 42 whereof is supported loosely upon the hub like portion 43 of the base plate or portion 44 of the head 25. The plate gear 41 is provided at its lower face at its outer edge with gear teeth 45 meshing with and driving a series of beveled pinions 46 corresponding in number to the number of yarns or threads fed to the machine,—that is, to the number of yarn or thread packages 24. The said beveled pinions 46 are supported in circular series, and each is fast upon the inner end of a short horizontal shaft 47 having suitable bearing in the upright flange 48 of the base plate 44 of the head 25. Each of the said short shafts 47 extends through a bracket 49 individual to each shaft 47, and which is itself supported by a fixed stud or rod 50, one end of which is secured by set screw 51 in a suitable socket 52 in said bracket. Each stud or rod 50 is in substantial parallelism with its shaft 47

and its inner end is secured by set screw 52 in the lower part of the flange 48 of the head 25.

The shafts 47 radiate from the head 25, as clearly indicated in Fig. 4, and thus each supports in proper position a pair of said feed rolls. Upon the other end of each shaft 47 is fast one roll 53 of a pair of such feed rolls. Said feed rolls may be of any suitable nature, but are now for best results provided with teeth, such as shown at 54 on feed roll 53, and the rolls are preferably slightly conical as indicated. Each feed roll 53 may at its inner end or base abut against the bracket 49 pertaining thereto. The teeth 54 of each roll 53 mesh throughout their entire length or a suitable portion of their length only with the teeth 55 of a similar feed roll 56 constituting the other member of the pair, and which is loose upon a short stud shaft 57 mounted as hereinafter described. Thus, one member of each pair of feed rolls 53, 56 is directly and positively driven, and the other member of each pair is driven from the driven member of the pair.

I have stated that the teeth of the rolls 53, 56 mesh throughout their entire length or any desired part thereof. The extent of meshing engagement of the teeth is desirably controlled through manual adjustment. For this purpose I desirably render the roll 56 adjustable toward and from the roll 53, and for this purpose, as shown most clearly in Figs. 7 and 8, I have mounted the stud 57 upon the arm 58 of the bell-crank lever 59 itself pivoted at 60 upon the bracket 49 and having an arm 61 extending in substantial parallelism with the edge of the bracket 49, as shown clearly in Fig. 8. Said arm 61 is provided with an opening 62 near its end receiving a threaded pin 63, the inner end of which is tapped into an opening in the bracket 49. The outer end of said pin 63 receives an adjusting nut 64 and a check nut 65, by means of which the extent of meshing of the roll 56 with the roll 53 may be very accurately determined. Desirably I provide a coil spring 66 between the arm 61 of the bell crank lever 59 and the bracket 49, tending to move said arm 61 outward.

Each pair of feed rolls 53, 56 is so positioned that a fixed thread guide for introducing the yarn or thread between the rolls is preferably in exact line with the axis of the yarn package 24 pertaining to said feed rolls, such axially positioned guide being for best results the guide 6 nearest the upper or delivery end of the said yarn package.

This relation of parts is clearly indicated in Figs. 2 and 9. If desired and as shown in said Figs. 2 and 9, I provide an arm 67 which extends from the head 25, as shown in Fig. 1 and terminates in an eye consti-

tuting a knot catcher but permitting the ready passage of the thread or yarn with sufficient freedom and lateral motion to take care of the ballooning thereof.

- 5 The eye or opening in the end of the arm 67 is itself as already indicated desirably exactly in line with the vertical axis of the corresponding yarn package 24 and is of the sufficiently large size indicated.
- 10 Herein shown as immediately above the eye in said arm 67, if said arm be employed, and directly in line with the vertical axis of the corresponding yarn package 24 if the arm 67 with its eye be not provided, is
- 15 the eye or guide 68 of a fixed but manually adjustable arm 69. Said eye or guide 68 is relatively close to the bight or meshing line of the feed rolls 53, 56, as hereinafter explained, and I have herein shown the
- 20 yarn or thread 70 from the yarn package 24 as passing through said eye 68 at a point in line with the vertical axis of said yarn package 24, but I am not necessarily limited to this construction. The said yarn
- 25 or thread 70 passes between the pair of feed rolls 53, 56 and at the opposite side of said rolls passes through the eye 71 of a second arm 72 desirably corresponding in all respects to the arm 69 and likewise manually
- 30 adjustable, but as hereinafter pointed out, it is not so important that the eye 71 be relatively close to the bight of the feed rolls 53, 56.

In Fig. 6, I have shown the preferred means for manually adjusting the arm 69, and it is to be understood that the arm 72 is similarly adjustable. As clearly shown in Fig. 6, the arm 69 is provided with an elongated slot 73 through which passes a pin or screw 74 adjustably received in the bracket 49. The construction is such that by loosening the pin or screw 74, arm 69 may be slid in a direction lengthwise the slot or turned so as to bring it into the desired position lengthwise of the feed rolls 53, 56, but in line with the bight thereof, after which the pin or screw 74 is tightened, thus securing the said arm 69 fixedly in position.

The yarn or thread is in the operation of the machine positively drawn from each yarn package 24 by the rotation of the feed rolls 53, 56 pertaining thereto. The distance between the upper end of the yarn package 24 and the eye or guide 68 of the arm 69 (or the eye in the arm 67 if employed) should for best results not be greater than about twelve inches nor less than six inches. If the distance be less than six inches, the yarn in ballooning off the yarn package 24 will strike the top of the yarn package and ultimately break from this cause. If, on the other hand, the top of the yarn package 24 be more than about twelve inches below the eye or guide 68 (or the eye in the arm 67), a compound ballooning effect results

which in itself prevents the proper feeding of the yarn.

Thus, it will be observed that there is a short length of yarn between each yarn package 24 and its pair of feed rolls 53 70 and 56. Desirably directly above each pair of feed rolls is a suitable yarn guide 80 and the yarn after passing through the eye of such guide 80 extends downward as indicated at 81 to the corresponding arm 17 75 of the stop motion passing through the eyes 20 and 21 thereof, as clearly indicated in the diagrammatic views Figs. 9 and 10. As already stated, the yarn in passing through the eyes 20, 21 is guided to the outer face 80 of the ring 19. Below said ring 19 is desirably positioned still another ring 82 and the yarn passes thereover directly to the needles of the machine a relatively short distance 85 therefrom, through guide 82'.

The fixed but manually adjustable finger 69 has its eye or guide 68 of sufficient size for the yarn to pass through freely. As stated, this eye or the eye in arm 67 if the latter be employed is in vertical alignment 90 with the axis of the yarn package 24 beneath it and the yarn is fed off the package by a ballooning motion inherent in the feed of yarn. Such ballooning motion causes a constant fluttering of the yarn in the eye 95 or guide 68. Such fluttering may be somewhat reduced if the arm 67 is provided, but in any case a flutter always exists of the yarn or thread in said eye or guide 68, and thus there is a constant slight flutter of the 100 yarn as it enters the bight of the feed rolls 53, 56. This slight flutter is apparently caused by the ballooning of the yarn or thread as it leaves the yarn package 24 and is always present.

The ballooning of the yarn off its package and local irregularities in feed of the yarn off its package due to such causes as slight variations in the tension of the yarn or slight variations at intervals in the diameter of the same yarn, cause a constant fluttering of the yarn at the eye in the arm 67, if such arm be provided, and at the eye 68. This constant fluttering is, as I have stated, 110 absorbed or compensated for by the several vibratory members 17. It is important, therefore, that this fluttering of the yarn or thread does not break the yarn or thread at the feed rolls, as would be the case if the eye 68 were not so constructed and were not so located with respect to the feed rolls at the in-feeding side as to permit the slight fluttering of the yarn to be rectified, compensated or taken care of at the vibratory members 17. Thus, not only should the size of the opening in the eye 68 or other guide be such as to permit the yarn to pass with sufficient freedom, but said eye or other guide should not be so close up to the bight of the feed rolls that there is not sufficient distance 120 125 130

between said eye or other guide and said bight of the rolls that the periodic and sudden fluttering causes the feed rolls suddenly to exert an increase or different positive feed to the yarn or thread, and thereby breaking it.

While not restricting myself to any exact measurements or proportions, I state for purposes of illustration that the opening in the guide eye or equivalent guiding member is desirably from $2/32''$ to $4/32''$, and with such size of guide eye, I may feed any yarn or thread from single 6's, cotton number to a single thread of one end Japan silk, which is equivalent to a single 340 cotton. Desirably the eye 68 should be at least $1\frac{1}{4}''$ or more from the bight of the feed rolls, if I rely upon vibratory members, as herein explained, to compensate for the fluttering of the yarn. The said eye 68 or other guide for the yarn at the infeeding side of the feed rolls must be far enough from the bight of said rolls to permit the yarn to vibrate or flutter between the said eye and the said feed rolls.

As stated, the yarn or thread passes from the feed rolls 53, 56 up through a guide 80, and then down through the pivoted arm 17 of the stop motion and then to the needles. The said pivoted arm 17 of the stop motion has a very slight oscillating movement which exactly takes up the slight flutter of the yarn at the feed rolls. Thus, if the parts work properly, the said slight flutter is taken care of by the movement of the stop arm 17, so that there is a direct cooperation between the parts and including a stop motion having a movable arm or member.

With the yarn positively fed as described any breaking of the yarn, as, for example, from the existence of a knot therein, always occurs between the supply package 24 and the pair of feed rolls 53, 56 pertaining thereto, and there is a sufficient extent or length of yarn between said feed rolls and the needles to prevent any press-off. That is, there is sufficient length of the yarn or thread between said feed rolls and the needles to permit the machine to be brought to rest by the operation of the stop mechanism before the broken end of the yarn reaches the needles. It will be evident from the drawings that the length of yarn between each pair of the feed rolls 53 and 56 and the needles is a number of times greater than the length of yarn between said feed rolls and the yarn package 24. Desirably each yarn package 24 is placed about ten inches above the dial plate of the machine, and each yarn or thread, after passing through the feed rolls, runs several feet before it reaches the needles.

So far as I am aware, I am the first to confine any break of the yarn or thread between the yarn supply or package and posi-

tive feed rolls or members for the yarn or thread.

For simplicity of operation, the stop mechanism which in itself may be of any desired type, but involving a movable arm or member, is actuated by the same arm which takes care of or absorbs or compensates for the fluttering of the yarn or thread. Referring to the disclosed form of stop motion, it is evident that the vibrating arm 17 of the stop motion, which arm functions to absorb, take care of or compensate for the fluttering of the yarn, is itself connected with the stop motion, so as to stop the machine in the event of an undue movement of said arm. Thus there is in effect a very intimate cooperation of a movable arm or member of the stop motion with the positive feed, such cooperation being in effect a double one, in that said movable arm first takes care of, absorbs or compensates for the constant fluttering to which I have referred, and second, said arm actuates the stop motion proper.

In Fig. 11 I have indicated three positions of the arm 17 marked *a*, *b* and *c*. The positions *a* and *b* correspond to and illustrate the constant vibration of the arm incident to the fluttering of the yarn or thread. The position *c* indicates the position assumed by the arm 17, if the yarn breaks between the yarn package 24 and the feed rolls. The movement of the arm 17 to the position *c* acts through movement of a wire or rod 83, shown in Fig. 1, to turn through suitable mechanism an upright shaft 84, and thereby to effect the shifting of the belt from the fast pulley 33 to the loose pulley 34 in a manner which need not be more fully described.

In Figs. 12 to 15 inclusive, I have shown a modified embodiment of a portion of my mechanism and constituting the preferred embodiment.

In Figs. 5 to 8 inclusive, I have represented each set of feed rolls as composed of two rolls. In the modified form of the invention, I have represented each set of rolls as composed of three rolls which are so arranged that the thread cannot slip but is fed with essentially absolute accuracy.

Such of the parts as are common to the construction shown in Figs. 12 to 15 and Figs. 5 to 8 are in the former figures represented by the same reference numeral with a prime attached. Except as now to be described, the construction is desirably the same as that shown in Figs. 5 to 8.

The shaft 47' shown most clearly in Figs. 14 and 15 has fast thereon the feed roll 53' and positioned therebelow is the roll 56'. Mounted above the roll 53' is an additional feed roll 85 mounted for rotation from or by the roll 53'. Said roll 85 is pivoted at 86 upon an arm 87 itself pivoted at 88. The

arm 87 constitutes one arm of a bell crank lever 89, the other arm 90 whereof is provided with an opening through which passes a threaded pin 91 upon which are the adjusting nut 92 and the lock nut 93. In this respect the construction is similar to that shown in Figs. 7 and 8.

The thread as shown most clearly in Fig. 13 enters through an eye 68^a in an arm 61^a 10 itself rigidly secured at 94 to an arm 95 pivoted for turning adjustment at 96. The arm 61^a is provided at its opposite end with an eye 97. The thread as shown in Fig. 13 is introduced between the feed roll 53' and 15 the feed roll 56' and passing about the roll 53' and between said roll and the feed roll 85 passes through the eye 97, and thence toward the point of use. After passing between the rolls 53' and 56' the thread passes 20 through a guide 98 supported in any suitable manner.

What has previously been said with respect to the form and construction of the pair of feed rolls equally applies with respect to the triple set of feed rolls. Preferably the toothed formation of rolls is employed.

Having thus described one illustrative embodiment of my invention, I desire it to 30 be understood that although specific terms are employed, they are used in a generic and descriptive sense and not for purposes of limitation, the scope of the invention being set forth in the following claims.

35 Claims:

1. Positive yarn feed and press-off preventing mechanism for knitting machines comprising, in combination, means to support one or more yarn packages, positive yarn feeding means acting continuously to feed 40 the yarn and located respectively relatively close to said yarn package or packages, a guide for each yarn at each positive feeding means and constructed and located sufficiently distant from said feeding means to accommodate the ballooning or other local irregularities of delivery of the yarn off its package and thus to permit the consequent fluttering of the yarn at said feeding means, and 45 stop motion means between the needles and the positive feeding means and having a vibratory yarn receiving member, only the minimum or normal vibratory movements whereof compensate for and absorb the said fluttering movement of the yarn at the positive feeding means and excess or abnormal vibratory 50 movements whereof serve to stop the knitting mechanism, the distance between the positive yarn feeding means and the needles having such relation to the length of yarn between 55 the yarn package and the positive yarn feeding means as to prevent press-off upon occurrence of yarn break between a yarn package and the corresponding positive 60 yarn feeding means.

2. Positive yarn feeding and press-off preventing mechanism for knitting machines comprising, in combination, means to support one or more yarn packages, positive yarn feeding rolls acting continuously to feed 70 the yarn and arranged in pairs respectively close to said yarn package or packages, a guide for each yarn at such feed rolls and constructed and located sufficiently distant from said feed rolls to accommodate the ballooning or other local irregularities of delivery of the yarn off its package and thus to permit consequent fluttering of the yarn at said feeding rolls, and stop motion means between the needles 75 and the pairs of positive feeding rolls and having a vibratory yarn receiving member, only the minimum or normal vibratory movements whereof compensate for and absorb the said fluttering movements of the yarn at 80 the positive feeding means and excess or abnormal vibratory movements whereof serve to stop the knitting mechanism, the distance between the positive yarn feeding means and the needles having such relation 85 to the length of yarn between the yarn package and the positive yarn feeding means as to prevent press-off upon occurrence of yarn break between a yarn package and the corresponding positive 90 yarn feeding means.

3. Positive yarn feed and press-off preventing mechanism for knitting machines comprising in combination, means to support one or more yarn packages, a pair of toothed feed rolls relatively close to the yarn package or packages and between which the yarn is positively fed, a guide for each yarn at its feed rolls and constructed and located sufficiently distant from said feed rolls to accommodate ballooning or other irregularities of 100 delivery of the yarn off its package and thus to permit consequent fluttering of the yarn at said feeding rolls, and stop motion means between the needles and the pairs of positive feeding rolls and having a vibratory yarn receiving member, only the minimum or normal vibratory movements whereof compensate for and absorb the said fluttering movements of the yarn at the positive feeding means and excess or abnormal vibratory 105 movements whereof serve to stop the knitting mechanism, the distance between the positive yarn feeding means and the needles having such relation to the length of yarn between 110 the yarn package and the positive yarn feeding means as to prevent press-off upon occurrence of yarn break between a yarn package and the corresponding positive 115 yarn feeding means.

4. Positive yarn feed and press-off preventing mechanism for knitting machines comprising, in combination, means to support one or more yarn packages, a pair of toothed feed rolls acting continuously to feed 120 the yarn and located respectively close to said 125 yarn and having such relation to the length of yarn between the yarn package and the positive yarn feeding means as to prevent press-off upon occurrence of yarn break between a yarn package and the corresponding positive 130 yarn feeding means.

- yarn package or packages with means for positively driving one member of each pair of rolls, thereby to effect the positive feeding of the yarn between the rolls, a guide for each 5
yarn at such feed rolls and constructed and located sufficiently distant from said feed rolls to accommodate the ballooning or other local irregularities of delivery of the yarn off its package and thus to permit consequent 10
fluttering of the yarn at said feeding rolls, and stop motion means between the needles and the pairs of positive feeding rolls and having a vibratory yarn receiving member, only the minimum or normal vibratory movements whereof compensate for and absorb the said fluttering movement of the yarn at the positive feeding means and excess or abnormal vibratory movements whereof serve to stop the knitting mechanism, the distance between the positive 15
yarn feeding means and the needles having such relation to the length of 70
yarn between the yarn package and the positive yarn feeding means as to prevent press-off upon occurrence of yarn break between a 75
yarn package and the corresponding positive 80
yarn feeding means.
15 5. Positive yarn feed and press-off preventing mechanism for knitting machines comprising, in combination, means to support one or more 85
yarn packages upon vertical axes, positive 90
yarn feeding means acting continuously to feed the yarn and located respectively relatively close to said yarn package or packages and positioned respectively directly over said package or packages, a stationary guide for 95
each yarn at its yarn feeding means, and constructed and located sufficiently distant from said feeding means to accommodate ballooning or other local irregularities of delivery 100
of the yarn for its package and thus to permit consequent fluttering of the yarn at said feeding means, such guide being directly in line with the vertical axis of its yarn package, 105
stop motion means between the needles and the positive feeding means and having a vibratory yarn receiving member, only the minimum or normal vibratory movements whereof compensate for and absorb the said fluttering movement of the yarn at the positive 110
feeding means and excess or abnormal vibratory movements whereof serve to stop the knitting mechanism, the distance between the positive 115
yarn feeding means and the needles having such relation to the length of yarn between the yarn package and the positive 120
yarn feeding means as to prevent press-off upon the occurrence of yarn break between a yarn package and the corresponding positive 125
yarn feeding means.
15 6. Positive yarn feed and press-off preventing mechanism for knitting machines comprising, in combination, means to support one or more 130
yarn packages with their longitudinal axes vertical, a pair of positive yarn feeding rolls acting continuously to feed the yarn and located respectively close to said yarn packages and directly thereover, a fixed but manually adjustable guide for each yarn at its pair of feed rolls and having its eye in line with the vertical axis of said yarn package, and con-

from said feeding means to accommodate the ballooning or other local irregularities of delivery of the yarn off its package and thus to permit the consequent fluttering of the yarn at said feeding means, and stop motion means between the needles and the positive feeding means and having a vibratory yarn receiving member, only the minimum or normal vibratory movements whereof compensate for and absorb the said fluttering movement of the yarn at the positive feeding means and the needles having such relation to the length of yarn between the yarn package and the positive yarn feeding means as to prevent press-off upon the occurrence of yarn break between a yarn package and the corresponding positive yarn feeding means.

7. Positive yarn feed and press-off mechanism for knitting machines comprising in combination, means to support one or more yarn packages upon vertical axes, positive 90
yarn feeding means acting continuously to feed the yarn and located respectively relatively close to said yarn package or packages and positioned respectively directly over said package or packages, a stationary guide for 95
each yarn at its yarn feeding means, and constructed and located sufficiently distant from said feeding means to accommodate ballooning or other local irregularities of delivery 100
of the yarn for its package and thus to permit consequent fluttering of the yarn at said feeding means, such guide being directly in line with the vertical axis of its yarn package, 105
stop motion means between the needles and the positive feeding means and having a vibratory yarn receiving member, only the minimum or normal vibratory movements whereof compensate for and absorb the said fluttering movement of the yarn at the positive 110
feeding means and excess or abnormal vibratory movements whereof serve to stop the knitting mechanism, the distance between the positive 115
yarn feeding means and the needles having such relation to the length of yarn between the yarn package and the positive 120
yarn feeding means as to prevent press-off upon the occurrence of yarn break between a yarn package and the corresponding positive 125
yarn feeding means.

8. Positive yarn feed and press-off mechanism for knitting machines comprising in combination, means to support a plurality of yarn packages with their longitudinal axes vertical, a pair of positive yarn feeding rolls acting continuously to feed the yarn and located respectively close to said yarn packages and directly thereover, a fixed but manually adjustable guide for each yarn at its pair of feed rolls and having its eye in line with the vertical axis of said yarn package, and con-

- structed and located sufficiently distant from said feeding rolls to accommodate the ballooning or other local irregularities of delivery of the yarn off such package and thus 5 to permit the consequent fluttering of the yarn at said feeding rolls, stop motion means between the needles and the pair of positive feeding rolls, and having a vibratory yarn receiving member, only the minimum or normal vibratory movements whereof compensate for and absorb the said fluttering movements of the yarn at the yarn feeding rolls, the distance between the positive yarn feeding means and the needles having such relation to the length of yarn between the yarn package and the positive yarn feeding means 15 as to prevent press-off upon occurrence of yarn break between a yarn package and the corresponding positive yarn feeding means.
- 20 9. Positive yarn feeding and press-off preventing mechanism for knitting machines comprising in combination, means to support one or more yarn packages, positive yarn feeding means acting continuously to feed the yarn and located respectively close to said yarn package or packages, a guide for each yarn at each positive feeding means and constructed and located sufficiently distant from said feeding means to accommodate ballooning or other local irregularities of delivery of the yarn off its package and thus to permit the consequent fluttering of the yarn at said feeding means, the said guide at each said feeding means having a fixed position but being manually incrementally adjustable along said feeding means, and stop motion means between the needles and the positive feeding means and having a vibratory yarn receiving member, only the minimum or normal vibratory movements whereof compensate for and absorb the said fluttering movement of the yarn at the positive feeding means, and excess or abnormal vibratory movements whereof serve to stop the knitting mechanism, the distance between the said positive yarn feeding means and the needles having such relation to the length of yarn between the yarn package and the positive yarn feeding means as to prevent press-off upon the occurrence of yarn break between a yarn package and a corresponding positive yarn feeding means.
- 45 10. Positive yarn feed and press-off preventing mechanism for knitting machines comprising, in combination, means to support one or more yarn packages, a plurality of tapering feed rolls between and by which the yarn is positively fed continuously to the needles, said feed rolls being respectively located relatively close to said yarn package or packages, a guide for each yarn at said feeding rolls and constructed and located sufficiently distant from said feed rolls to accommodate the ballooning or other local irregularities of delivery of the yarn off its package and thus to permit the consequent fluttering of the yarn off its package and thus to permit the consequent fluttering of the yarn at said feeding means, each said guide having a fixed position relatively close to the meeting line of said rolls but being manually incrementally adjustable therealong, and stop motion means between the needles and said rolls and having a vibratory yarn-receiving member, only the minimum or normal vibratory movements whereof compensate for and absorb the said fluttering movement of the yarn at the said rolls, and excess or abnormal vibratory movement whereof serve to stop the mechanism, the distance between said rolls and the needles having such relation to the length of yarn between the yarn package and the said rolls as to prevent press-off upon the occurrence of yarn break between the yarn package and the corresponding rolls.
- 50 11. Positive yarn feed and press-off preventing mechanism for knitting machines comprising in combination, means to support one or more yarn packages, positive yarn feeding means acting continuously to feed the yarn and located respectively close to said yarn package or packages, a guide for each yarn at each positive feeding means and constructed and located sufficiently distant from said feeding means to accommodate the ballooning or other local irregularities of delivery of the yarn off its package and thus to permit the consequent fluttering of the yarn at said feeding means, and a fluttering-absorption vibratory member positioned between said feeding means and the needles and acting to receive the yarn and compensate for and absorb the said fluttering movement of the yarn at the positive feeding means, the distance between said positive yarn feeding means and the needles having such relation to the length of yarn between the yarn package and the positive yarn feeding means as to prevent press-off upon the occurrence of yarn break between a yarn package and a corresponding positive yarn feeding means.
- 55 12. Positive yarn feeding and press-off preventing mechanism for knitting machines comprising in combination, means to support one or more yarn packages, a plurality of tapering feed rolls for each yarn between and by which the yarn is positively and continuously fed to the needles, said feed rolls being respectively relatively close to the corresponding yarn package, a guide for each yarn occupying a fixed position relatively close to the meeting line of the feed rolls but manually incrementally adjustable therealong, such guide being constructed and located sufficiently distant from said feed rolls to accommodate the ballooning or other local irregularities of delivery of the yarn off its package and thus to permit the consequent fluttering of the yarn at

said feeding means, and a fluttering-absorption vibratory member to receive the yarn on its way from said feeding rolls to the needles and serving to compensate for and absorb the said fluttering movement of the yarn at the positive feeding means at the said feed rolls, the distance between said feed rolls and the needles having such relation

to the length of yarn between the yarn package and the feed rolls pertaining thereto as to prevent press-off upon the occurrence of yarn break between a yarn package and its feed rolls. 10

In testimony whereof, I have signed my name to this specification.

WILLIAM P. DRUMHELLER.
